UNITED STATES PATENT OFFICE

FREDERICK B. WALTER, OF WABASH, INDIANA, ASSIGNOR TO B. WALTER & COMPANY, INC., OF WABASH, INDIANA, A CORPORATION OF INDIANA

TABLE SLIDE SUPPORT

Application filed May 8, 1929. Serial No. 361,318.

My invention relates to improvements in extension tables and particularly to the means for supporting the extension leaves thereof.

5 My invention relates particularly to that type of extension table wherein the leaves are adapted to be slid under the table when not in use and which when drawn from beneath the table are raised to a level to the 10 table top.

It is one of the objects of my invention to provide a supporting means for those leaves which will permit them to slide in and out of position and which will support the same 15 in such a manner that they may be readily raised or lowered for operating purposes.

For the purpose of disclosing my invention, I have illustrated one embodiment thereof in the accompanying drawings in which:

20 Fig. 1 is a bottom plan view of a table embodying my invention;

Fig. 2 is a longitudinal sectional view showing the leaves extended and lying in the same plane as the table top;

25 Fig. 3 is a sectional view showing the leaves depressed and lying beneath the table top and

Fig. 4 is a detailed elevation of the leaf supported.

30 In the embodiment of the invention illustrated, I provide a suitable support or table base 1. The table top 3 is rigidly supported on this base in the usual manner. The table is provided with leaves 4 and 5, one at 35 each end, which are mounted on suitable slides for permitting them to be moved from storage to extension position and vice versa.

To this end each leaf is provided with a pair of suitable slides 6 on which the leaf is 40 mounted. These movable slides cooperate with relatively stationary slides 7 which are connected together by cross-bars 8 and 9. The opposite slides of each leaf are provided with racks 10 and 11 geared together by 45 means of pinions 12 so that, the two leaves are moved in unison.

The slide unit is supported for vertical movement on a pair of supporting members, one on each side of the table. Each of these 50 members comprise a plate 13 having a right

angle lip 14 formed on the bottom thereof by which it may be secured to the table base. Pivoted to this plate is a pair of levers 15 and 16, the pivots 17 of which are at opposite edges of the plate. These levers are 55 pivotally connected together as at 18 and the lever 15 is provided at its outer end with a U shaped clip 19 which is secured on the end of the lever by a pivot pin 20 and provided with a securing bolt 21. A similar clip 60 22 having a bolt 23 is connected to the opposite lever 16 by means of a link 24 pivoted at one end to the clip and at the other end to an upwardly extending lug 25. Each of the levers 15 and 16 has an offset ear 26 preferably pivoted in position and this ear has extending therethrough a bolt 27, the head of which is threaded into a coiled spring 28, the opposite end of which is connected to a stud 29 extending from the side plate near 70 its upper edge. It is noted that each spring and its connection with the lever extends at an angle thereto.

In assembly, a support is arranged on each side of the table. The lip 14 is bolted or 75 screwed to the base to position the plate 13 vertically. One of the U-shaped clips is connected to the end of one of the cross-bars 8 of the slide unit, the bolt of the clip being adapted to be passed through the cross-bars 80 and the clip of the opposite lever is connected in a similar manner to the end of the opposite cross-bars 9 of the slide unit. By this arrangement, the slide unit and the table leaves are supported on the levers so that, 85 the slide unit and leaves may be moved vertically. The strength of each spring is counter-balanced by the weight of the leaves and the slide unit and due to the change of angular position of each of the leaves, when 90 the leaves are raised or lowered, the ratio of leverage exerted increases or decreases, depending upon the position of the leaves, to compensate for the increase and decrease in tension of the spring so that the leaves will 95 remain in whichever extreme position to which they may be moved. In operation the leaves are normally depressed and maintained in their storage position beneath the table. When it is desired to extend the leaves they 100

are pulled out and by a slight upward pressure are raised to a level with the table top, after which they may be moved toward the table top to interlock therewith. When it is desired to move the leaves to their storage position they are pulled out from their interlocking connection with the table top and by a slight pressure will be caused to drop to their lowered level and may be moved back to their storage position. The pivotal connection 18 is loose enough to permit the two levers to swing about their respective pivots 17.

I claim as my invention:

1. The combination with a table base, of a table top mounted on said base, a table leaf, a slide unit support for said leaf to permit the same to slide in planes parallel with said top, a lever for supporting said slide unit pivoted on said base and having one end connected to said slide unit to permit said unit to move vertically, and a spring anchored at one end and connected at its other end to said lever, the tension of said spring and the weight of the leaf and slide unit being so related as to sustain said leaf in either of the two extreme vertical positions to which it may be moved.

2. The combination with a table base, of a table top mounted on said base, a table leaf, a slide unit support for said leaf to permit said leaf to slide in planes parallel with said top, a lever for supporting said unit having one end pivoted on said base and the opposite end connected to the slide unit and a spring angularly disposed relatively to the lever and having one end anchored and the opposite end connected to the lever.

3. The combination with a table base, of a table top mounted on said base, a table leaf, a slide unit support for said table leaf to permit said leaf to slide in planes parallel to said top, a lever for supporting said slide unit pivoted on said base and having one end connected to said unit, a spring having one end anchored and the other end connected to said lever, the angular relation between said spring and lever being such that the leverage exerted on said spring by the movement of said lever varies with the change in tension on the spring.

4. The combination with a table base, of a table top mounted on said base, a pair of table leaves, a slide unit for supporting said leaves, a pair of oppositely extending levers for supporting said slide unit pivotally mounted on the base and having their ends pivotally connected, the opposite ends of said levers being connected to the slide unit, and a pair of springs having one end anchored and their opposite ends respectively connected to said levers, the tension of said springs and the weight of said unit and leaves being so related as to sustain said leaves in either

of the two extreme vertical positions to which they may be adjusted.

5. An extension-table leaf-support comprising a main plate, two oppositely extending lever arms pivoted upon said main plate with their inner ends pivoted together, two clips, one carried by the outer end of each of said levers, and a tension spring anchored at one end upon the base plate and at the other end upon one of said levers.

In witness whereof, I, FREDERICK B. WALTER, have hereunto set my hand at Wabash, Indiana, this 6th day of April, A. D. one thousand nine hundred and twenty-nine.

FREDERICK B. WALTER.
